BRAKE BEAM SUPPORT CHAIR

Edwin G. Busse, Chicago, Ill., assignor to Chicago Railway Equipment Company, Chicago, Ill., a corporation of Illinois

Application July 3, 1939, Serial No. 282,603

19 Claims. (Cl. 188—213)

The invention relates to railway rolling stock brake beams and consists in a novel support chair adapted to be applied to the compression and tension members of a truss type brake beam at a point between the beam strut and the brake head and arranged to contact with a bar underlying the beam for guiding the beam in its movement to and from the wheels, thereby maintaining the desired angular relation between the 5 brake shoes and the wheels. Also, in the event the usual brake hanger fails, the device may function to support the beam and prevent the beam dropping to the rail and creating a hazard during the further travel of the car.

10 One object of the invention is to provide a support chair of the type referred to which may be applied to beam members of substantially different cross sections to snugly fit any one of a plurality of such members whereby a single support chair may be used interchangeably upon 15 different beams.

Another object of the invention is to avoid loss of the support chair in the event that its holding element loosens or is accidentally removed. 20 Another object of the invention is to prevent the substantial displacement of the support chair along the beam. These and other detailed objects of the invention are attained by the structure illustrated in the accompanying drawings in 25 which—

Figure 1 is a top view of a truss type brake beam provided with fourth point support chairs of the type described herein. Parts of the adjacent truck frame and chair support structure 30 are also shown.

Figure 2 is a vertical section taken on line 2—2 of Figure 1.

Figures 3 and 4 are similar sections illustrating the same support chair assembled with brake 35 beams having compression members of different cross sections than that shown in Figures 1 and 2.

Figure 5 is an end view of the device looking at the same from the right hand end of Figure 2.

Figure 6 is a vertical section taken on line 6—6 40 of Figure 2.

Figure 7 is a horizontal section taken on the line 7—7 of Figure 2.

Figure 8 is a section similar to Figure 2 but showing a form of the invention arranged for 45 an angle section beam member in addition to the U, channel and T sections.

Figure 9 is a section corresponding to Figure 2 but showing a different form of the invention with the two parts hinged to each other above 50 the beam.

Figure 10 is a top view of the right hand end of the beam as shown in Figure 1 but drawn to an enlarged scale, and with the chair device sectioned to better illustrate one feature of the invention.

Figure 11 is a vertical section taken on the line 11—11 of Figure 10.

The brake beam includes a U shaped compression member 1, a round rod tension member 2, a strut 3, brake heads 4 and tensioning nuts 5 threaded on tension rod 2 and seated on the outer faces of brake heads 4. Portions of the truck frame are indicated at 6 and include brackets 7 which mount flat bars 8 extending longitudinally of the truck beneath the brake beam and constitute safety and guide devices.

All of the above parts are of familiar section and in themselves do not constitute any part of the present invention.

The fourth point support chair, cooperating 20 with the beam and the bars 8, consists of two main parts, a body 9 and a jaw 10 having overlapping ears 11 and 12 respectively, pivotally connected by a pin 13. Body 9 includes an extension 14 forming a shoe adapted to engage and 25 slide upon a bar 8 and thereby maintains the desired angularity of the brake beam in its movement to and from the truck wheels.

A bolt 15 extends through lugs 16 and 17 on body 9 and jaw 10 and constitutes means for 30 clamping the beam compression member 1 in the chair. Jaw 10 has two short arcuate elements 18 arranged to engage spaced points on the curved rear face of U shaped compression member 1, and the opposing portion of chair body 9 has a straight element 19 arranged to engage the edges of legs of the compression member. When bolt 15 is tightened, the compression member is tightly gripped between elements 18 and 19.

Body 9 also includes a recessed portion 20 arranged to snugly receive the round tension member 2 of the brake beam, and by arranging recess 20 as best indicated in the top view, Figure 1, the device is arranged for application to the left 45 hand or right hand end of the beam.

When clamped in position on the beam the chair will be held stably against movement along the beam or transversely of the beam, either in straight or rotational directions.

If desired, the chair may be applied to a channel shape compression member, as indicated at 50 21 in Figure 3, the opposing faces of the body and jaw having elements 22 and 23 respectively arranged to engage opposing points on the com-

5

40

50

55

pression member to stably contact the same. Elements 22 and 23 are spaced from elements 18 and 19 previously referred to.

- If desired, the chair may be applied to a brake beam compression member of T section, as indicated at 24 in Figure 4. In such application the leg of the T is received in a recess 25 provided in jaw 10 and the cross arm of the T engages elements 26 on body 9 spaced apart sufficiently to provide a stable bearing for the beam member but still close enough together to be received between the flanges of the U section compression member or the channel section compression member.
- 15 The opposing faces of the chair body and clamping jaw may be further modified, as indicated in Figure 8, to seat and securely hold a beam member 30 of angle section. In this form of the invention the upwardly and downwardly facing elements at the top and bottom of the chair body 31 are recessed, as shown at 32, to receive the edges of the beam member. The corner portion of the beam may be received in a recess 25 which also receives the T leg, and 20 the adjacent face of the jaw may be flattened at 33 to firmly seat the angle legs near the corner. This angle type of beam compression member is not being adopted on new beams at this time and it may be preferable to omit recesses 32 25 and flats 33 provided for the same so that the chair body and jaw elements which engage the beam compression members of different cross sections may provide for greater contact area. Figure 8 illustrates how the device may be shaped to accommodate four different sections of beam members. It will be understood that the chair parts may be shaped to seat different beam members of similar section but of different dimensions.

Figure 9 illustrates a form of the invention in 40 which the upper parts 35 and 36 of the body and jaw are extended towards each other to overlap and to receive a hinged pin 37 while the lower portions 38 and 39 form spaced ears for receiving the clamping bolt 40.

45 With the arrangements previously described, loosening of the nut will not affect the assembly of the device but if the nut should work off of the bolt and the bolt work out of the jaw parts, eventually the hinged portion of the chair would 50 drop backward and downward and permit the chair to work away from the brake head and then drop off. This could not happen with the two parts hinged to each other at the top of the compression member, as shown in Figure 9.

55 With this construction the bolt receiving ears project downwardly from the beam a greater distance than the hinged lugs in the other forms of the invention. To provide clearance between the beam clamping parts of the chair and the 60 supporting bar 41, it may be necessary to extend the latter downwardly and place an extra bend in the same, as indicated at 42 to avoid any change in the mounting of the bar upon the spring plank 43 or other truck parts to which 65 the bar is attached. However, this additional downward extension of the bar may not be required, in which case the contour of the bar would be the same as shown in Figure 2.

70 Figures 10 and 11 illustrate more clearly than is illustrated in Figure 1 how the body portion of the chair securely engages upwardly, downwardly and outwardly facing portions of the beam tension and compression members to hold the assembled parts against movement along the beam. The inclined elements 45 and 46 resist

movement of the chair towards the brake head irrespective of contact between the beam and the chair jaw member 10. Movement of the chair away from the head is prevented by elements 47 and 48 inclined in the opposite direction. 5 If the chair is mounted on the other end of the beam then the functioning of elements 45, 46, 47 and 48 would be reversed. The lip 49 at the upper end of recess 20 overlies the top of the beam tension member and not only helps 10 prevent movement of the chair along the brake beam but it prevents the accidental pulling away or dislocation of shoe 14 in the handling of the brake beams.

15 Each application of the chair indicates metal to metal contact between the same and the beam members, but it will be understood that inserts of rubber or other packing material may be placed between the contacting metal parts to break up vibration and avoid loosening up of 20 the clamping bolt nut. Inserts of this type are illustrated in Patent 2,067,596 issued to the present inventor January 12, 1937, but such inserts are not essential to the present device and are omitted from the drawings to avoid confusion.

25 The details of the chair may be varied without departing from the spirit of the invention and the exclusive use of such modifications as come within the scope of the claims is contemplated.

30 What is claimed is:

1. A support chair device arranged to extend between the compression and tension members of a truss type brake beam and including a pair of separately formed parts permanently assembled and movable relative to each other, and means for clamping a beam member between said parts, at least one of said parts being constructed and arranged to engage both of the brake beam members, irrespective of said clamping means, to provide support for the device against accidental 40 dropping to the roadbed.

2. A support chair device arranged to extend between the compression and tension members of a truss type brake beam and comprising a part arranged to overlie both of the brake beam members to prevent the device from falling to the roadbed, said part including an element arranged to ride on a support bar, and means permanently assembled with said part and co-operating therewith to grip one of the brake 50 beam members and maintain the assembly of the device and brake beam.

3. A support chair device for application to a truss type brake beam and comprising a body part constructed and arranged to extend between 55 and overlie the compression and tension members of the beam, there being a projection on one of said parts for slidably engaging a supporting bar, and means pivotally secured to said part and cooperating therewith to clamp a portion of the 60 beam to maintain the assembly of the device and beam.

4. In a support chair for a truss type brake beam, a part arranged to extend between the compression and tension members of the beam 65 and provided with a depending shoe arranged to slidably engage a supporting bar, one end of said part having elements arranged to fit snugly against brake beam members of different cross sections.

5. In a support chair for a railway brake beam, parts hinged to each other and provided with opposing elements arranged to cooperate to snugly engage spaced points on a beam member having one cross section, there being other elements 75

on said parts disposed to cooperate to snugly engage spaced points on another beam member having a different cross section.

6. In a support chair for a railway truss type 5
brake beam, a body part arranged to extend between beam compression and tension members, a jaw hinged to said body part and having elements for engaging spaced points on a beam member to maintain assembly of the beam and chair, said jaw having other elements for engaging spaced points on another beam member having a different cross section to maintain assembly 10
of the beam and chair.

7. In a support chair for a truss type brake 15
beam, a part arranged to extend between the compression and tension members of the beam and provided with a depending shoe arranged to slidably engage a supporting bar, one end of said part having elements arranged to seat the edges 20
of the legs of a beam member of U shape cross section, there being lugs arranged to extend between said legs and disposed to seat the cross bar of a beam member of T shape cross section, and means for clamping either beam member against 25
the corresponding elements of said part.

8. In a support chair for a truss type brake beam, a part arranged to extend between the compression and tension members of the beam and provided with a depending shoe arranged to slidably engage a supporting bar, one end of said part having elements arranged to seat the edges 30
of the legs of a beam member of U shape cross section, there being other elements arranged to seat the edges of a beam member of channel 35
shape cross section, and means for clamping either beam member against the corresponding elements of said part.

9. A device as described in claim 8 in which the beam clamping means comprise a jaw hinged 40
to the chair part and having curved elements arranged to engage the bottom portion of a U shape beam member, and having straight elements adjacent said curved elements arranged to seat the bottom portion of a channel shape beam member.

10. A device as described in claim 7 in which 45
the beam clamping means comprise a jaw hinged to the chair part and having curved elements arranged to engage the bottom portion of a U shape beam member, and having a recess between its U beam-seating curved elements arranged to receive the leg of a beam member of T section.

11. In a support chair for a truss type brake beam, a part arranged to extend between the compression and tension members of the beam and provided with a depending shoe arranged to slidably engage a supporting bar, one end of said part having elements arranged to seat the edges 55
of the legs of a beam member of U shape cross section, and adjacent elements arranged to seat the edges of the legs of a beam member of channel shape cross section, and adjacent elements arranged to seat the edges of a beam member of angle shape cross section, and a jaw hinged to said part and having curved elements arranged to form a snug fit for the back of a U beam member, and a seat fit for the back of a channel beam member, and a snug fit for the back of an angle beam member.

12. A fourth point support chair for a railway 70
truss type brake beam including a rigid body portion arranged to extend transversely of beam compression and tension members inclined to each other and to be supported thereby, and having elements arranged to fit against and overlie

both of the inclined beam members irrespective of the end of the beam to which the chair is applied.

13. In a device of the class described, a rigid 5
arm arranged to extend transversely of the compression and tension members of a truss type 10
brake beam and arranged to receive and overhang the beam tension member, the front and rear ends of said opening having convexly V shaped faces whereby the tension member may be engaged by an element at one side of the center line of the arm and inclined towards one side of the arm and may be engaged by an element inclined towards the other side of the arm, there being corresponding elements inclined to 15
engage the tension member if the device is placed at the other end of the beam.

14. In combination a railway truss type brake beam including a compression member, a tension member and a fourth point support chair including a body part extending between said tension beam members, there being a jaw pivoted to said body part and cooperating therewith to enclose one of said beam members, said jaw having a member opposing contour arranged to fit snugly 25
with brake beam members of different cross sections.

15. In a railway truss type brake beam assembly, a compression and a tension member, and a transversely disposed chair snugly mounted on 30
said members and including parts movable relative to each other to inclose and clamp one of said members, each of said parts including elements arranged to cooperate with opposing elements on the other part to firmly seat brake beam 35
members of different cross sections.

16. In combination, a railway truss type brake beam including a compression member and a tension member, and a fourth point support chair comprising a support engaging shoe and a rigid body part and a jaw hinged thereto, said part and jaw each being arranged to overlie the beam and said part and jaw having elements arranged to cooperate to clamp between them one of the beam members, and said body part having rigid 40
faces for engaging opposing surfaces of both beam members and to overlie portions of both members, the beam clamping elements and said faces cooperating to prevent movement of the chair longitudinally of the beam irrespective of 45
a tight grip by the clamping elements.

17. In a support chair of the type described, a rigid body part comprising a support engaging shoe and elements arranged to extend between and overlie both the compression and tension members of a beam, and having a depending shoe for engaging a supporting bar.

18. In a support chair of the type described, a part arranged to extend between and overlie the compression and tension members of the beam, and a bar-engaging shoe depending from said body part, a jaw hinged to the portion of said body part arranged to overlie the compression member of the beam, said body part and jaw having elements arranged to contact with the lower portion of the compression member of the beam, and means for clamping said beam member between said body part and jaw.

19. A support chair as described in claim 18 in which the beam clamping portions of the body 70
part and jaw include elements arranged respectively to fit snugly against brake beam members of different cross sections.

EDWIN G. BUSSE.
